ALARM AND WATCHMEN SYSTEM

Pasqual Di Orio and Max Schmidhofer, Chicago, Ill., assignors of one-fifth to Charles Michel, one-fifth to Roswell O. Byenum, and one-fifth to Ernst E. Schmidhofer, all of Chicago, Ill.

Application January 17, 1931, Serial No. 509,342

4 Claims. (Cl. 161—20)

This invention relates to alarm and watchmen systems.

In the use of present systems of the above type where the condition of a plurality of outlying stations is supervised from a central station, a relatively large force is required at the central station to check the reports from the outlying stations and it is highly desirable to eliminate the necessity of this force as far as possible.

10 The primary object of this invention is accordingly to provide for the automatic registration and recording at the central station of the station which fails to report on time.

Another object of this invention is to provide in 15 a system and apparatus of the above type for the automatic control of the time element of the mechanism at the outlying stations from the central station and for the automatic detection of any failure of such control.

20 A further object is to provide for the automatic winding of the watchman's box and the prevention of over-winding thereof.

Another object of this invention is to provide 25 means for adjusting the system to any selected time at which it is desired to have the watchmen attend and/or report at the respective stations.

Other and further objects of this invention will 30 be apparent as the same becomes better understood from an examination of the specification and claims in connection with the accompanying drawings, wherein:—

Fig. 1 represents a rear elevation of the mechanism in the individual watchman boxes;

Fig. 2 is a side elevation of same with parts 35 omitted;

Fig. 3 is a fragmentary side view of the same with parts omitted and showing the automatic winding apparatus;

Fig. 4 is a similar plan view of the winding ap- 40 paratus;

Fig. 5 is a fragmentary elevational view partly schematic, showing the mechanism for operating the watchman's box from the master clock at the subscriber's station;

45 Fig. 6 is a view partly schematic, showing the apparatus for recording the failure of the watchman to register at the prescribed time and for recording other data;

Fig. 7 is a view of the device adapted to coop- 50 erate with pendulum of master clock to close circuit shown in Fig. 11 to indicate stopping of master clock;

Fig. 7a is a detail view of part of the structure shown in Fig. 7;

55 Fig. 8 is a perspective detail view of device for

closing impulse circuit shown in Fig. 5 for operating watchman's box in accordance with master clock;

Fig. 9 is an enlarged detail view of time cam on watchman's box and means for adjusting same;

Fig. 10 is a section taken at the line 10—10 of Fig. 9; and

Fig. 11 is a schematic view showing the apparatus including that of Fig. 7 in circuit for indicating any stopping of the master clock.

Referring to the drawings more particularly, reference character 1 (Fig. 1) represents a time cam adjustably mounted on a shaft 2 journaled on a plate 3, the latter being connected to a similar plate 4 and spaced therefrom by braces 5, the plates 3 and 4 and braces 5 forming a suitable mount for the mechanism in the watchman's box. The shaft 2 is driven one complete rotation every hour through the intermediary of a gear 6 thereon having sixty teeth, each representing one minute. This gear is driven by mechanism to be described hereinafter in connection with Figs. 5 and 8.

When the watchman at one of the subscriber stations has "pulled the box" at the prescribed time, that is, inserted his key (not shown) in receptacle 7 (Fig. 2) carried by plate 4 to drive shaft 8 through suitable means in said receptacle to cause pinion 9 on said shaft to rotate, no registration or record will result at the central station.

When the pinion 9 revolves by reason of the watchman using his key, gear 11 rotatably mounted in plate 4 is caused to revolve, bringing a pin 12 on said gear in contact with an arm 13 on a shaft 14, causing a second arm 15 on said shaft to actuate a lever 16 from position "a" in Fig. 1 to dotted line position "b" therein, allowing a slidable member 17 shown in alignment with said lever to move inwardly under the action of a spring 18. The member 17 is carried in a guide 19 mounted on plate 3 and carries a pin 21 adapted to engage an abutment 22 on a bar 23. The bar 23 is slidably carried in a guide member 24 mounted on plate 3 and its upper end is provided with a roller 25 which rides on a lever 26 pivoted on plate 3 with its free end riding on the cam 1. The cam 1 is provided with a drop 27 at the point on its periphery corresponding to the time before which the watchman is required to "pull his box", but when the pin 21 is engaged beneath the abutment 22 the bar 23 will not drop even when the lever 26 drops at the point 27.

If the watchman has not "pulled his box" as described and the lever 16 is allowed to remain 55

in the full line position shown with the pin 21 out of engagement with the abutment 22 when the position 27 on the cam passes beneath the free end of the lever 26, the bar 23 will drop with said lever, causing an arm 28 on the bar to actuate a lever 29 on the plate 3. The lever 29 when thus actuated will in turn actuate a lever 31 carrying a pin 32 against a spring 33 to remove said pin from a recess in a notched hollow disc 34 driven by a spring motor 34a therein connected to shaft 82 to thereby release said motor. In other words disc 34 and one end of spring 34a are fixed to shaft 82. This motor 34a is provided with cams 35 and 36 respectively, as shown in Fig. 6, which are driven in unison. Cam 35 is cut to provide the registration and recording of the watchman's box number, as will be hereinafter described in connection with Fig. 6. The member 17 and lever 16 are returned to the position shown about fifteen minutes before the point 27 on the cam reaches the free end of the lever 26, a pin 10 on said cam engaging a pin 20 on said member.

If the watchman desires to transmit a fire-alarm he manually operates a handle 37 to rotate a shaft 38 provided with a small cam 39 which operates a bell crank lever 41 on the plate 3 to likewise actuate the lever 31 to release the motor 34a. The cam 36 is cut to provide the fire signal and the shaft 38 is provided with an additional cam 40. This cam 40 normally renders a lever 42 pivotally mounted on plate 10a inoperative to respond to the configurations of the cam 36 but when actuated by the fire handle 37 it permits the separation of contacts 43 associated with said lever in accordance with said configurations to correspondingly control a switch by means of a magnet 45 in circuit with said contacts. A similar lever 46 is provided in conjunction with the cam 35 adapted to break associated contacts 47 in accordance with the configurations of the cam. These contacts are also in circuit with the magnet 45 and a source of current whereby the switch 44 will be operated in accordance with the configurations on the cam 35. The cams 35 and 36 are mounted so that their depressions will occur in succession with those of one cam at a spaced interval from those of the other. The switch 44 is in circuit with a recording device 48 of standard type, a source of current and a visible indicator such as an electric light bulb 49 all at the central station, whereby the station or box number where the watchman fails to "pull in" will be indicated and recorded at the central office and when a fire handle is operated at the box the fire signal as well as the station or box number will be indicated and recorded at the central office.

The mechanisms in the watchmen's boxes are time-controlled from the subscriber's office, a master clock therein being provided with cams 51 and 52 (Fig. 8) in juxtaposition on a shaft 53 of the master clock which makes one revolution per minute. These cams are provided with drop positions 54 and 55, respectively, the latter occurring at a slight time interval behind the former so that a pivoted lever 56 having an electrical contact 57 thereon and riding on the cam 54 may be actuated to bring said contact in engagement with a contact 58 on a second lever 59 riding on the cam 52. When the desired interval of contact has elapsed, the lever 59 dropping over the position 55, the contacts 57 and 58 will be separated. These contacts 57 and 58 are as shown in Fig. 5 in circuit with a magnet 75 61 at each watchman's box whereby an impulse

is delivered each minute to actuate an armature 62 on a bell crank lever provided also with a hook-shaped member 63 for advancing the gear 6 one tooth per minute. The lever carrying the armature 62 and member 63 is provided with a yieldable pivot, it being pivoted on the free end of a lever 64 and provided with a spring 65 yieldably drawing it toward the center of the gear 6. A spring pressed pawl 66 is provided to prevent back-lash.

Since the master clock at the subscriber's office controls the entire system, means are provided to indicate any failure of the master clock. This means is illustrated in Figs. 7 and 11. The pendulum 67 of the master clock (not shown) is provided with a trough-like projection 68. A small pendulum 69 skips over the projection 68 with each swing but should the pendulum 67 stop the pendulum 69 will engage in the trough just prior to stoppage of the large pendulum and be actuated, causing a pivoted lever 71 to rise and allow a pivoted weight 72 to drop and keep said lever in the up position. The lever 71 carries an insulated contact 73 which when said lever is in up position engages a similar contact 74. These contacts as shown in Fig. 11 are in circuit with a source of current 75 and a magnet 76 whereby when the latter is energized it will actuate an armature 77 provided with a pin 78. The pin 78 normally locks a spring motor 79 and when the armature 77 is actuated said motor is released. The motor 79 is connected with suitable alarm devices.

Means are provided to prevent over-winding of the spring motor 34a by the watchman as he automatically winds it when "pulling in". As previously stated, when the watchman "pulls in" by inserting his key in the receptacle 7 and rotates pinion 9, he also rotates gear 11. As gear 11 is thus rotated a gear 81 on a small shaft 82 in alignment with the shaft of the former and connected thereto by a slidible coupling 83 is also caused to revolve. This gear 81 is on the same shaft as spring motor 34a and when thus rotated causes the winding of said motor. A gear 84 in mesh with gear 81 and provided with diametrically opposed projections 85 and 86 is adapted to control the coupling 83 to cause the same to disconnect the shaft 82 when the spring motor is fully wound and to connect with said shaft when the motor is run down. A bell crank lever 87 pivoted on a suitable support between plates 3 and 4 has one arm operatively connected to the coupling 83 in a peripheral groove thereof and its other end provided with a pin 88 adapted to be engaged by the projection 85 when the motor 34a is wound to slide the coupling 83 to the right to disconnected position, the pin 88 being adapted to be engaged by the projection 86 when the motor is run down to return the coupling to connected position.

In order that the cam 1 (Figs. 1, 2, 9 and 10) may be adjusted to require the watchman to "pull in" at any desired period during the hour (if the watchman does not "pull in" before point 27 on the cam reaches the free end of the lever 26 an alarm will be given and the delinquency will be recorded at the central office as previously explained), said cam is mounted on a sleeve 89 on the shaft 2 and is held against a collar 91 thereon by an apertured boss 92. This boss 92 is fitted over a squared extension 93 on the shaft 2 whereby it is fixed against rotation relative to said shaft and is removably held thereon by a nut 94 cooperating with a threaded portion exteriorly of the 70 75 80 85 90 95 100

extension 93. The boss 92 is provided with a pair of diametrical oppositely extending claws 95 adapted to engage in any opposite pair of grooves in circular member 96 (the same being provided 5 with sixty peripheral equi-spaced grooves 97 and being integrally connected to the cam 1).

The operation and advantages of the afore-described system and apparatus will be apparent without further detail.

10 We are aware that many changes may be made and many details varied without departing from the spirit of our invention and we therefore do not wish to be limited to the details shown or described.

15 We claim:—

1. In an apparatus of the character described, the combination of an indicator, a spring motor, means for winding said motor, means for automatically disconnecting the winding means from 20 the motor when the same is wound, and means including said motor for operating said indicator after a predetermined time when the motor winding means has not been operated within that time.

2. In an apparatus of the character described, 25 the combination of an indicator, a spring motor, means for winding said motor, means for automatically disconnecting the winding means from the motor when the same is wound, and for connecting the said means to the motor when the same becomes unwound, and means including said

motor for operating said indicator after a predetermined time when the motor winding means has not been operated within that time.

3. In an apparatus of the character described, 5 the combination with a time controlled element, of a spring motor, means for winding said motor, means for automatically disconnecting the winding means from the motor when the same is wound, signal transmitting means, means for operating said transmitting means periodically by 10 said element and means controlled by said first means for preventing the operation of the transmitting means for a predetermined period after the motor has been wound.

4. In an apparatus of the character described, 15 the combination with a time controlled element, of a spring motor, means for winding said motor, and means for automatically disconnecting the winding means from the motor when the same is wound and for connecting said means to the 20 motor when the same becomes unwound, signal transmitting means, means for operating said transmitting means periodically by said element and means controlled by said first means for preventing the operation of the transmitting means 25 for a predetermined period after the motor has been wound.

PASQUAL DI ORIO.
MAX SCHMIDHOFER.

CERTIFICATE OF CORRECTION.

Patent No. 1,996,698.

April 2, 1935.

PASQUAL DI ORIO, ET AL.

It is hereby certified that the name of the second-named assignee in the above numbered patent was erroneously written and printed as "Roswell O. Byenum" whereas said name should have been written and printed as Roswell O. Byerrum, as shown by the record of assignments in this office; and that the said Letters Patent should be read with this correction therein that the same may conform to the record of the case in the Patent Office.

Signed and sealed this 18th day of June, A. D. 1935.

Leslie Frazer
